(57) **CLAIM**

The ornamental design for a storage cabinet, as shown and described.

DESCRIPTION

FIG. 1 is a front, right, and top perspective view of a storage cabinet showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is another perspective view of the storage cabinet of FIG. 1, shown in an alternate configuration;

FIG. 12 is an enlarged view of portion 12 shown in FIG. 1; and,

FIG. 13 is an enlarged view of portion 13 shown in FIG. 3. The dash-dash broken lines in the drawings depict portions of the storage cabinet that form no part of the claimed design. The dot-dash broken lines shown in FIGS. 1, 3, 9, 10, 12, and 13 represent boundaries of the enlarged portion that form no part of the claimed design. The dot-dot-dash line and the right surfaces within the dot-dot dash line shown in FIG. 11 form no part of the claimed design.

1 Claim, 13 Drawing Sheets
